UNITED STATES PATENT OFFICE.

MICHAEL J. KANE, OF ST. PAUL, MINNESOTA.

PAPER BOX.

SPECIFICATION forming part of Letters Patent No. 642,128, dated January 30, 1900.

Application filed September 25, 1899. Serial No. 731,524. (No model.)

To all whom it may concern:

Be it known that I, MICHAEL J. KANE, a citizen of the United States, residing at St. Paul, in the county of Ramsey and State of Minnesota, have invented certain new and useful Improvements in Paper Boxes; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in folding boxes, and has especial reference to boxes made of paper and pasteboard.

The object of the invention is to provide a cheap folding box of so simple a construction that it may be easily and quickly knocked down and set up by any ordinary person, even unskilled clerks or assistants. This object I attain by the novel construction and arrangement of parts illustrated in the accompanying drawings, in which—

Figure 1 is a perspective view of my improved box, made of pasteboard. Fig. 2 is a bottom view of Fig. 1 slightly modified. Fig. 3 is a side view of Fig. 1 knocked down with bottom folded out or downward. Fig. 4 is the same as Fig. 3, but the sides G are folded inward. Fig. 5 is Fig. 2 with bottom folded in or upward. Fig. 6 is Fig. 2 with bottom folded out or downward. Fig. 7 are blanks of body and bottom of box slightly separated. Fig. 8 is a modification of Fig. 7 and corresponds to Figs. 1, 3, and 4.

Referring to the drawings by letters of reference, A designates the cover of the box, and as it is of common construction, either plain or folding, as may be desired, it is shown only in Fig. 1 and needs no further description.

B is the bottom of the box. It may be a plain four-cornered piece, as in Fig. 7, with a central folding crease or joint C, or it may have two opposite flaps D D, Fig. 8, or even four such flaps, including those marked E E in said Fig. 8.

The body of the box, which may be made in one or two or more pieces and pasted together in any desired manner, comprises two opposite solid sides F F and two opposite sides G G, with vertical central folding creases, in-

cisions, or joints C' falling in line with the central crease C in the bottom and in the flaps E, which may follow the sides G, as in Figs. 52, 5, 6, and 7. My preferred style is that shown in Fig. 7, where it will be seen that the box is built by pasting the ends I and J of the body-blank together and then pasting the bottom with its edges H H upon the flaps E E of the body-blank. The bottom may then be folded outward, as in Fig. 6, or inward, as in Fig. 5, and the sides G may be folded outward, as in Fig. 5, or inward, as in Fig. 4, and when the box is set up it is simply opened to assume its normal shape, the flaps E are bent inward, as in Fig. 2, to stiffen and support the adjacent edges of the bottom and of the folding sides G, and the flaps are secured in that position by the tape K, which is inserted in the slits L in the bottom, traverses the inner side of the bottom, and has its outwardly-projecting ends passed over the flaps E and up the sides of the box and united by a knot upon the cover in the usual manner for similar boxes.

Instead of having the slits L in the center crease C they may be cut slightly to one side therefrom, like M M or N N in Fig. 8. Two tapes may be used, one at M and the other at N, or one tape may be passed from one of the slits M to the diagonally-opposite slit N, as indicated by the dotted lines O in Fig. 8.

Fig. 8 illustrates that the box may also be made from a body-blank consisting of a plain strip of pasteboard by pasting the ends I and J of it together and then pasting the flaps D D of the bottom to the edges P P of the body, so that the folding-crease C falls in line with the creases C' in the body-blank, and the box 90 after receiving its tape and cover is ready for use, as in Fig. 1, with the flaps E turned upward and held by the tape K. When this box is empty, it may be folded for transportation either as in Figs. 3 or 4 indicated.

It will be understood that the folding outward or inward of the sides and bottom of the box is much a matter of taste and depends on which way the joints, creases, or incisions are made from the outer or inner side 100 of the blanks. The flaps E serve the same purpose whether they are made as in Fig. 1 or in Fig. 2. All corners of the box are folding.

Having thus described my invention, what

I claim, and desire to secure by Letters Patent, is—

1. A box having four folding corners, two opposite solid sides, and two opposite sides being loose from the bottom and folding at a central vertical line; the bottom of the box being secured in a folding manner to the two solid sides of the body, and having a central folding joint or crease in plane with the vertical central folding-creases in the sides, substantially as set forth.

2. A box having folding corners, two opposite solid sides, and two opposite sides being loose from the bottom and folding at a central vertical line, a bottom secured in a folding manner to the base of the solid sides, and having a central folding joint or crease in line with the vertical joints in the sides, and the folding flaps E, for covering and supporting the adjacent loose edges of the centrally-folding sides and bottom, substantially as set forth.

3. A box having folding corners, two opposite solid sides, and two opposite sides being loose from the bottom and folding at a central vertical line, a bottom secured in a folding manner to the base of the solid sides, and having a central folding joint or crease in

line with the central vertical joints in the sides, the flaps E, E, supporting the adjacent loose edges of the folding sides and the bottom, and the tape, or tapes, inserted in the bottom, crossing said flaps E, and being adapted to have the ends passed upward and tied together on the top of the box, substantially as and for the purpose described.

4. A box having folding corners, two opposite solid sides, and two opposite sides being loose from the bottom and folding at a central vertical line, a bottom secured in a folding manner to the base of the solid sides, and having a central folding joint or crease in line with the central vertical creases in the sides, the flaps E, E, projecting out from the bottom of the box and being adapted to fold up to the centrally-creased sides, and a tape or tapes secured in the bottom, crossing said flaps and being adapted to have the ends passed upward and tied together upon the top of the box.

In testimony whereof I affix my signature in presence of two witnesses.

MICHAEL J. KANE.
